UNITED STATES PATENT OFFICE

100,587

DESIGN FOR A CASEMENT HINGE

Charles E. Spencer, Chicago, and Owen W. Roberts, Oak Park, Ill., assignors to Casement Hardware Co., Chicago, Ill., a corporation of Illinois

Application May 22, 1936, Serial No. 62,789

Term of patent 7 years

To all whom it may concern:

Be it known that we, Charles E. Spencer and Owen W. Roberts, citizens of the United States, residing at Chicago and Oak Park, respectively, in the county of Cook and State of Illinois, have invented a new, original, and ornamental Design for a Casement Hinge, of which the following is a specification, reference being had to the accompanying drawing forming part thereof.

The figures are elevational views of a casement hinge embodying our new design—these views

illustrating the hinge as it appears when its two principal members, disposed at right angles to each other, are viewed from different directions.

We claim:

The ornamental design for a casement hinge, as shown.

In witness whereof, we hereunto subscribe our names, this 19th day of May, 1936.

CHARLES E. SPENCER.
OWEN W. ROBERTS.
